(57) **CLAIM**

The ornamental design for a surveillance camera, as shown and described.

DESCRIPTION

FIG. 1 is an exploded front, left perspective view of a surveillance camera showing my new design;

FIG. 2 is a left side view of the surveillance camera shown assembled;

FIG. 3 is another exploded front, left perspective view of the surveillance camera, showing the base in an alternative position;

FIG. 4 is a rear view of the surveillance camera shown assembled in an alternate configuration;

FIG. 5 is a front view of the surveillance camera, showing the camera separate from the base to show aspects of the design that are not visible when combined;

FIG. 6 is a rear elevational view thereof;

FIG. 7 is a left side view thereof;

FIG. 8 is a right side view thereof;

FIG. 9 is an enlarged top plan view thereof;

FIG. 10 is an enlarged bottom plan view thereof;

FIG. 11 is a front, left perspective view showing the surveillance camera in FIG. 5;

FIG. 12 is a rear, left perspective view thereof;

FIG. 13 is a bottom, left perspective view thereof;

FIG. 14 is a bottom view of the surveillance camera, showing the base separate from the camera to show aspects of the design that are not visible when combined;

FIG. 15 is a top plan view thereof;

FIG. 16 is a left side view thereof;

FIG. 17 is a right side view thereof;

FIG. 18 is a front view thereof;

FIG. 19 is a front view thereof;

FIG. 20 is a bottom, right perspective view thereof; and,

FIG. 21 is a top, left perspective view thereof.

The broken lines shown in the drawings depict portions of the surveillance camera that form no part of the claimed design.

1 Claim, 16 Drawing Sheets
